UNITED STATES PATENT OFFICE.

JOHN ALBERT TILTON, OF STANSTEAD, QUEBEC, CANADA.

PORTABLE FENCE.

Application filed October 31, 1927. Serial No. 230,099.

This invention relates to new and useful improvements in play-yards for children and an object of the invention is to provide a plurality of fence sections which may be readily assembled to form an enclosure or yard in which a child may safely play.

A further object is to provide an article of the character described, comprising fence sections which are of flexiform construction and 10 loosely riveted so as to yield to pressure and fold into compact form.

Another object of the invention is to provide an article of the class described having fence-sections composed of vertical slats 15 which are absolutely unclimbable.

Other objects and many of the attendant advantages will be readily appreciated as the invention becomes better understood from a careful consideration of the illustrative embodiments of the same and for which purpose such descriptive drawings have been hereto appended, wherein:

Figure 1 is a perspective view of this novel play-yard.

Figure 2 is an elevation of some of the fence-sections connected to a standard.

Figure 3 is a view of a fence-section folded into compact form.

Figure 4 is a detailed view of the gate latch.

Referring more in detail to the drawings in which similar reference numerals designate the corresponding parts throughout the several views.

It will be seen that the device comprises a series of fence-sections 6 secured to standards 7, and a suitable gate 8 provided with a latch device.

The fence-sections 6 are of peculiar and novel construction, each section comprising a plurality of vertically disposed slats 9 arranged in spaced relation and loosely held at the tops and bottoms thereof between the horizontally opposed slats 10 by rivets 11 or the like in a manner to be rigid in spaced relation one to the other yet subject to pivotal action.

The standards 7 are of common construction and are provided with fastening elements which receive and hold the related end 50 of the opposed fence-sections. These fastening elements are attached only to the faces of the standards which receive the related fence-sections thereagainst and each element comprises a spike 12 rigidly secured 55 to the standard and having its outward ex-

tremity angularly bent at 13 and directed upward in a manner to constitute a hook and receive the relative end of the bottom, horizontal slats 10 therein. The spikes 12 which are located at the top of the standards are 60 rotatable so that the angularly bent extremity 13 may be swung from engagement with the top horizontal slat to facilitate removal of the particular fence-section 6.

The gate 8 is of similar construction to 65 the fence-sections, and comprises vertical slats 14 arranged in spaced relation and loosely held at the tops and bottoms thereof, between the horizontal opposed slats 15 by rivets 16 in a manner to be rigid in spaced 70 relation one to the other yet subject to pivotal action. This gate 8 is hinged at 17 to standard A and is locked from swinging action by a complex arrangement carried by standard B. The standard B has a longitudinal vertical rib 19 formed on one face over which are engaged the projecting ends of the horizontal slats 15, forming the double upper and lower members of the gate when the gate is in a closed position. To lock the 75 gate in its closed position the latch device 18 pivotally mounted on the top of the standard B is swung into engagement with one of the vertical slats 14, as clearly shown in Fig. 4.

In opening this gate it will be seen that 80 the latch device 18 must first be swung free of the gate 8 then the gate is folded in a manner to tilt upward and disengage rib 19 and swing open upon hinges 17.

It will be realized that with these novelly 85 constructed fence-sections, the entire device can be folded into compact form for storing, transporting or the like.

It will be obvious from the foregoing description that this invention is a great improvement in play-yards for children and whilst the preferred embodiments have been described yet it must be understood that minor changes in the details of construction, combination and arrangement of the co-operating elements may be resorted to within 95 the scope of what is claimed without departing from the spirit of the invention.

I claim:

1. A play-yard comprising standards; 105 fastening elements disposed at the top and bottom of said standards, each of said elements comprising a spike having its outer extremity angularly bent to constitute a hook, said bottom element being rigid and 110

bent upwardly; collapsible fence sections having upper and lower horizontal slats, said bottom fastening elements providing a seat for said lower horizontal slats and said top fastening elements being rotatable to engage over said upper horizontal slats, whereby the fence sections are held in fixed relation to the standards.

2. A play-yard comprising standards; a plurality of collapsible fence sections secured to said standards, said sections comprising spaced vertical slats pivotally mounted at top and bottom between opposed

horizontal slats, one of said sections being hinged at one end to one of said standards the opposed standard having a longitudinal rib on one face over which are engaged the projecting ends of the horizontal slats when the section is extended, and a latch pivotally mounted on the top of said opposed standard adapted to be swung into engagement with the top of one of said vertical slats, whereby said section is locked in closed position.

In testimony whereof I affix my signature.

JOHN ALBERT TILTON.
